ATTORNEY.

UNITED STATES PATENT OFFICE.

JAMES A. PRIEST, OF UTICA, NEW YORK.

DESIGN FOR A NECKTIE ATTACHMENT.

SPECIFICATION forming part of Design No. 30,457, dated April 4, 1899.

Application filed March 6, 1899. Serial No. 708,039. Term of patent 7 years.

To all whom it may concern:

Be it known that I, JAMES A. PRIEST, a citizen of the United States, residing at Utica, in the county of Oneida and State of New York, have invented and produced a new and original Design for Necktie Attachments, of which the following is a specification, reference being had to the accompanying drawings, forming a part thereof.

Figure 1 shows a front view of the necktie attachment of my design. Fig. 2 shows a back or rear view of the same. Fig. 3 shows an end view of the same. Fig. 4 shows a perspective view at an angle from the front. Fig. 5 shows a perspective view of an angle from the rear.

The feature of the construction is the form, shape, and arrangement of the necktie attachment, as shown—that is to say, having the

side bar portions 1 1, the cross-bar portions 2, 20 carried by upwardly-turned portions 3 3 of the side bars, and also having the dependent doubled hooked portion 4, supported by the inwardly-turned upper ends of the bars 1 1, all as shown in the drawings. 25

Having described my invention, what I claim as new, and desire to secure by Letters Patent, is—

The design for a necktie attachment substantially as herein shown and described. 30

In witness whereof I have hereunto set my hand, in the presence of two witnesses, this 3d day of March, 1899.

JAMES A. PRIEST.

Witnesses:
